UNITED STATES PATENT OFFICE.

MAUD C. FOX, OF NEW YORK, N. Y.

DESIGN FOR A WALL-POT HOLDER.

Application filed May 9, 1928. Serial No. 26,612. Term of patent 3½ years.

To all whom it may concern:

Be it known that I, MAUD C. Fox, a citizen of the United States, residing at 181 Claremont Avenue, in the city and county of New York and State of New York, have invented a new, original, and ornamental Design for Wall-Pot Holders, of which the following is a specification, reference being had to the accompanying drawing, forming part thereof.

The figure is a perspective view of a wall pot holder, showing my new design.

I claim:

The ornamental design for a wall pot holder as shown.

MAUD C. FOX.
